CLAIM

The ornamental design for rifle as shown and described.

DESCRIPTION

FIG. 1 is a right side, rear, and top perspective view for rifle, showing my new design;

FIG. 2 is a left side, front, and top perspective view thereof;

FIG. 3 is a right side elevational view thereof;

FIG. 4 is a left side elevational view thereof;

FIG. 5 is a rear elevational view thereof, on a larger scale;

FIG. 6 is a front elevational view thereof, on a larger scale;

FIG. 7 is top plan view thereof;

FIG. 8 is bottom plan view thereof;

FIG. 9 is a rear-portion partial right side view thereof, on a larger scale;

FIG. 10 is a central-portion partial right side view thereof, on a larger scale;

FIG. 11 is a partial right side elevational view thereof, on a larger scale; and,

FIG. 12 is a partial left side elevational view thereof, on a larger scale.

The evenly spaced broken lines depict portions of a rifle that form no part of the claimed design. The dot-dash broken lines depict boundaries of enlargements that form no part of the claimed design.

1 Claim, 9 Drawing Sheets
